AUTOMATIC STACK TYPE AIR FILTER

Arthur Nutting, Louisville, Ky., assignor to American Air Filter Company, Inc., Louisville, Ky., corporation of Delaware

Application April 4, 1938, Serial No. 199,848

11 Claims. (Cl. 183—9)

This invention relates to air filters of the character wherein a series of filter units are arranged one over the other to form a vertical air filtering stack and means provided for removing the bottom unit of the stack at intervals and replacing it at the top.

The principal objects of the invention are to effect a substantial simplification in the structure of this type of air filter, to produce simple and dependable means for automatically removing and replacing a filter unit, to provide a novel stack supporting arrangement, and to provide a novel arrangement which permits one unit to soak while another unit is draining.

15 A further object of the invention is the provision of simple and dependable means for controlling and regulating the gravitational movement of the stack so as to lower it gradually and in proper timed relation.

20 The invention is illustrated in the accompanying drawings, wherein:

Figure 1 is a side elevation view of the lower portion of an air filter stack of the character mentioned, with my improvements applied thereto, the filter casing being broken away;

Figure 2 is a partial front elevational view of the filter shown in Figure 1; and

Figures 3, 4, 5 and 6 are reduced diagrammatic views similar to Figure 1, showing the entire filter stack and illustrating the manner of its operation.

The structure used to illustrate the invention comprises an upright casing 1, of more or less conventional design, and, therefore, provided with the customary air inlet and outlet openings 2 and 3 in its front and rear walls respectively, and an oil bath 4 in its bottom. Also conventionally illustrated are a series of air filter units 5, stacked one upon the other, to form a continuous air filter curtain across the front air inlet opening 2. The side and top edges of the stack, as a whole, frictionally engage the customary sealing strip 6 of the casing 1, while the bottom of the stack is sealed by its contact with the oil bath. The filter units 5 are preferably but not necessarily of the viscous impingement type. Both ends of each unit are provided with fore and aft pins or studs 7, which preferably are spaced at equal distances from each other and from the next adjacent guide pin of a contacting unit.

The studs 7 at each end of the units in the stack extend into a guideway 8 on the adjacent side wall of the casing. The guideway on one

guideway on the other side wall to prescribe the endless path along which the units ultimately travel. The shape of the guideways 8, which are of channel form, is such as to prescribe an endless path of travel which extends from the upper front part of the casing downwardly through the filtering or stack section into the oil bath, horizontally through a soaking section within the bath, upwardly out of the bath through a drainage section to the upper rear part of the 10 casing and thence laterally to the upper end of the filtering section, the lateral return section preferably being inclined obliquely downward toward the filtering section.

To support the units in stacked relation, mechanical means have heretofore been provided to engage and hold the bottom unit of the stack until actuated by some other mechanism to release the lowermost unit only to engage and hold the next unit as it moves downwardly into 15 the bottom position. In accordance with the present invention, however, such means is eliminated because the flat shape of the guideways 8 in the soaking section permits them to support the bottom unit in a horizontal position 20 underneath the stack, while the sharply curved shape of the guideways at the point of connection between filtering and soaking sections causes them to turn a downwardly moving unit from a vertical filtering position quickly to the 25 horizontal soaking and stack supporting position. As a result, the stack is supported on the soaking unit and remains in a fixed filtering position until such unit is removed, whereupon the weight 30 of the stack becomes effective to force the lowermost filtering unit into the soaking section, during which it is forced to assume the horizontal 35 stack supporting position vacated by the removed unit.

To prevent the sudden dropping of the stack, 40 when a bottom unit is removed, the air outlet face of each unit 5 may be provided at one edge, the lower edge when such unit is in the stack, with an outwardly projecting cam 9 presenting a rounded or cam face which ultimately 45 engages the adjacent and preferably rounded edge of the bottom unit of the stack as the latter is pulled from its stack supporting position.

Heretofore, either a pair of endless chain conveyors operating at different speeds, or a single 50 endless chain conveyor having special gears to alter its shape and path, has been provided to remove the bottom (horizontal) unit from the stack and convey it to the top of the stack. The present invention makes possible the use of a 55

single and simply shaped conveyor in place of such special conveyors. A straight-sided conveyor, for example, composed of a pair of vertically arranged laterally spaced endless sprocket chains 10 may be used. These chains are positioned within the housing preferably with their up sides adjacent the air outlet opening 3 in operative position relatively to the up side of the guideways 8 but with their down sides offset from the filtering stack. The chains 10 are mounted upon opposed pairs of lower and upper sprockets 11 and 12, which are respectively mounted on lower and upper shafts 11a and 12a, in the customary manner to be driven either continuously or intermittently by manually or mechanically operated means. In the preferred arrangement shown, a mechanical drive is provided, comprising a motor (not shown) suitably connected to one end of the upper shaft 12a. Any desired type of control mechanism may be provided to regulate or vary the operation of the motor.

The conveyor chains 10, which travel in the clockwise direction indicated by arrow T, each carry, at corresponding points along their length, a pair of closely associated fore and aft fingers 13 and 14. These fingers are secured to separate links of each chain to lie closely together along the straight portions of chain travel and move angularly apart along the curved portions thereof. They operate to engage the studs 7 of the filter units and to move them in the manner hereinafter described.

While the filter may be operated continuously or intermittently in any desired manner, its intermittent operation not only is preferred but preferably instituted when the parts are positioned as shown in Figure 3 and then continued through one complete uninterrupted cycle of operation which returns the fingers 13 and 14 to their Figure 3 position. With reference to Figure 3, then, it will be noted that the stack, composed of units 5C to 5G inclusive, is supported upon a horizontal unit 5B in the soaking section, while an additional unit 5A is vertically arranged in the drainage section. This unit is protected from the air flow by a shield 15 secured to the casing 1. While the drainage unit 5A may be supported in drainage position in any suitable manner, it can be conveniently supported by the forefingers 13 of the conveyor chains 10.

After it has been supported in such position for a suitable drainage period, the control operates automatically to set the conveyor in motion. The conveyor slowly carries unit 5A upwardly to the return section of the guideways 8. As the unit 5A moves into the inclined return section, it passes away from the conveyor and thus becomes disengaged from the fingers, ultimately reaching the top of the stack as shown in Figure 4.

The conveyor, however, continues to move downwardly, carrying the fingers 13 and 14 into the oil bath as shown in Figure 5. As the fingers 13 and 14 move around the lower sprocket 11, they not only enter the space between studs 7 of the soaking unit 5B but spread angularly apart to bridge the gap between such studs.

The continuing movement of the conveyor causes the forefingers 13 to pull the soaking unit 5B from underneath the stack. The weight of the stack now becomes effective to institute the downward movement of the lowermost vertical unit 5C from the filtering section toward the soaking section. In so doing, the unit 5C presses against the soaking unit 5B tending to thrust it

forward, but such forward thrusting movement of the soaking unit is prevented by the aft fingers 14 of the conveyor. At the same time, the conveyor operates through the aft finger 14 to control and restrain the gravitational movement of the stack as a whole.

As the conveyor continues to move the unit 5B toward the drainage position, the stack continues to move unit 5C toward the soaking position. As soon as unit 5C reaches the soaking position, its movement will cease, but the conveyor continues to move the unit 5B until it emerges completely from the oil bath and reaches the drainage position shown in Figure 6. This completes the cycle of operation; consequently, the conveyor is stopped until the next unit 5B completes its drainage whereupon the next cycle of operation may be instituted.

Although the aft finger 14, with or without the aid of cam 9 on the filter units, will ordinarily control the gravitational movement of the stack in a satisfactory manner, it may be desirable, in some cases, to secure greater uniformity in the rate at which the stack is lowered. For this reason additional stack restraining means are illustrated in the drawings. Such means includes a star or sprocket 16 mounted upon a hub 17, which is keyed to a rotatable shaft 18, the latter shaft being connected by sprocket chain 19 to a smaller sprocket 20 on lower conveyor shaft 11a. The position of star 16 is such that its teeth successively extend into the space between successive studs of the stack filter units as the stack is lowered. The star 16 is connected to hub 17 through a clutch which permits the star to remain stationary while the stack is stationary, even though the hub 17 is rotating, but prevents the star from rotating at a speed greater than that of the hub. This clutch may be of any well known type, such as shown in Figure 1, which comprises a tapered slot 21 formed in hub 17 and a ball 22 arranged in said slot. The taper of the slot is such as to decrease its depth in the direction of hub rotation, while the diameter of the ball is such as to connect the parts together in the shallow section of the slot and to release them in the deep section thereof.

The star 16 is thus adapted to remain stationary while the conveyor moves or to rotate as the conveyor moves, but is effectively prevented by the clutch from rotating at a speed greater than the rotational speed of the lower conveyor shaft 11a. As a result when the stack is supported by a unit in the soaking position, the star 16 is unable to rotate due to its engagement with the studs of units in the stationary stack; hence, it remains stationary even though the conveyor may be moving. However, when the conveyor in moving, pulls the soaking unit from its stack supporting position, the resulting sudden downward movement of the stack will tend to rotate the star 16 rapidly, at a rate faster than that of the hub 17 upon which the star is mounted. The initial movement of the star, however, rolls the ball 22 toward the shallow end of the tapered slot 21 and thus effectively secures the star to the hub. This necessarily compels the star to rotate with the hub 17 and limits the further lowering movement of the stack accordingly.

While the advantages of this structure will be readily appreciated, it may be noted that: the offset of the stack from the down side of the conveyor makes possible the employment of a straight sided conveyor with resulting simplification of structure; the laterally inclined top guide-

way provides a simple and yet effective way of disconnecting the unit from the conveyor and delivering it to the top of the stack; and the sharply curved connection between filter and soaking sections of the guideway and the flattening of the soaking section provide an effective way of turning a vertical unit quickly to, and holding it in, a horizontal soaking position wherein its rear end portion extends underneath the stack to support the same while its front end bridges the offset between the stack and the conveyor sufficiently to enable the latter to engage and remove the soaking unit. A particular feature of the invention is that it permits the use of the conveyor or other means for supporting a unit in the drainage position while another unit remains in the oil bath where it becomes thoroughly soaked and thus thoroughly cleaned of its dirt content. The arrangement of the soaking unit in stack supporting position is also highly advantageous, since it removal automatically causes the stack to be lowered and another unit to assume the stack supporting soaking position. The use of an extra finger on the conveyor provides a satisfactory means for controlling the downward movement of the stack, while the additional stack restraining means insures an effective way of lowering the stack in a slow or gradual manner. Structures of this character have the further advantage of always presenting the same face of the filtering units to the air flow; hence, the units not only may be progressively packed but may be replaced or re-packed from time to time to provide the same or different filtering density.

Having described my invention, I claim:

1. An air filter comprising: a casing having an air passageway; a filter unit horizontally arranged in the lower part of said casing; a stationary frame for supporting said unit; a stack of movable filter units vertically arranged one over the other across the passageway, said stack resting upon said horizontally arranged unit; means for removing the horizontal unit horizontally from underneath the stack and transferring it to the top of said stack; the weight of said stack causing it to move gravitationally downward upon the removal of said horizontal unit; and means for turning the downwardly moving lowermost vertical unit of the stack into the stack supporting horizontal position vacated by the removed unit.

2. An air filter of the character having a flat bottomed endless vertical path of unit travel, comprising: a filter unit horizontally arranged along the flat bottom of said path; stationary guideway means to support said unit; a stack of filter units vertically arranged one over the other along the down side of said path, said stack resting upon said horizontal unit; and means for removing the horizontal unit in a horizontal direction from underneath the stack and conveying it along said endless path to the top of the stack; said stack moving downward upon the removal of said horizontal unit; said guideway means frictionally engaging the lowermost vertical unit of the downwardly moving stack to turn such unit to the horizontal stack supporting position while it remains in contact with the succeeding vertical unit of the stack.

3. An air filter comprising: a casing having a bottom oil bath and an air passageway above said bath; a filter unit arranged to soak within said bath; a stationary frame for supporting said soaking unit; a stack of filter units ver-

tically arranged one over the other in air filtering position across the passageway, said stack resting upon said soaking unit; conveyor means operative, upon movement, to move the soaking unit horizontally from underneath the stack and transfer it to the top of the stack; said stack moving downward upon the removal of said soaking unit; means for guiding the downwardly moving lowermost vertical unit of the stack into the stack supporting soaking position vacated by the preceding soaking unit; and means for moving the conveyor.

4. An air filter comprising: a casing having a bottom oil bath and an air passageway above said bath; a filter unit arranged to soak within said bath; means for supporting said soaking unit; a stack of filter units vertically arranged one over the other in air filtering position across the passageway, said stack resting upon said soaking unit; a unit arranged in drainage position above said bath; means for supporting said draining unit; conveyor means operative, upon movement, to transfer the draining unit to the top of the stack and the soaking unit to the drainage position; said stack moving downward upon the removal of said soaking unit; means for guiding the downwardly moving lowermost vertical unit to the stack supporting soaking position vacated by the preceding soaking unit; and means for moving the conveyor.

5. An air filter comprising: a casing having a bottom oil bath and an air passageway above said bath; a filter unit horizontally arranged to soak within said bath; means for supporting said soaking unit; a stack of filter units vertically arranged one over the other across the passageway, said stack resting upon said soaking unit; a unit arranged in drainage position above said bath; means for supporting said draining unit; conveyor means operative, upon movement, to transfer the draining unit to the top of the stack and the soaking unit to the drainage position; said stack moving downward upon the removal of said soaking unit; means for turning the downwardly moving lowermost vertical unit of the stack horizontally into the stack supporting soaking position vacated by the preceding soaking unit; and means for moving the conveyor.

6. An air filter comprising: a casing having a bottom oil bath and an air flow passageway above said bath; guideway means prescribing an endless path of unit travel which extends from a top return section downwardly through a filtering section into the oil bath, horizontally through a soaking section within the bath and thence upwardly out of the bath through a drainage section to the top return section; a filter unit horizontally supported in the soaking section by the guideway means; a stack of filter units vertically arranged one over the other in the filtering section, said stack resting upon the soaking unit; a filter unit vertically arranged in the drainage section; a conveyor supporting the drainage unit in the drainage section, said conveyor being operative when moved to convey the drainage unit to and release it at the top return section and to convey the soaking unit to and support it in the drainage section; and means for so moving the conveyor; said stack being arranged for downward movement upon the removal of said soaking unit and said guideway means being operative to turn the downwardly moving lowermost vertical unit of the stack horizontally into the soaking stack supporting position.

7. An improvement in air filters of the type

wherein a forefinger is mounted on an endless conveyor for movement along a vertically arranged endless path, having straight and curved portions, during which it enters the space between fore and aft end studs of a filter unit at the fore end of a stack-forming series, which is mounted for vertical movement across an air duct, to remove such unit, convey it to and release it at the aft end thereof, comprising: an aft finger mounted on the conveyor adjacent the forefinger, the fore and aft fingers being arranged to lie closely together along the straight portions of conveyor travel, to spread angularly apart along the curved portions thereof, to enter the stud space before they are fully spread apart and substantially to bridge the stud space when fully spread.

8. An air filter comprising: means forming a fixed guideway having a vertical section, the lower end of which curves abruptly into a flat-bottomed horizontal section; a stack of filter units extending upwardly along said vertical section, said stack including a horizontally arranged unit resting on said horizontal section and a series of vertically arranged superposed units resting one upon the other with the lowermost vertical unit resting upon the horizontal unit due to the abruptness of the lower end curvature of said vertical section; and conveyor means for intermittently removing a unit at the lower end of the stack and replacing it at the other end thereof.

9. The air filter of claim 8, wherein: said conveyor means removes the bottom unit horizontally from underneath the stack; the units of the stack move gravitationally downward upon the removal of said horizontal unit; and said guideway means operates to turn the downwardly-moving lowermost vertical unit of the stack horizontally into the stack-supporting horizontal position vacated by the removed unit.

10. An air filter comprising: a frame; a horizontally arranged bottom filter unit removably

supported on said frame; a stack of movable filter units vertically arranged one over the other, said stack resting upon the aft upper-face portion of said bottom unit; a straight-sided conveyor, having symmetrically curved end portions, vertically arranged with its lower end adjacent the fore end of said bottom unit and with its downside offset from the vertical units of said stack; said conveyor being operative, when moved, to engage said bottom unit, transfer it to, and release it at, the top of the stack; means for moving the conveyor; the units of said stack moving gravitationally downward upon the removal of said bottom unit; and means for turning the downwardly moving lowermost vertical unit of the stack into the stack-supporting horizontal position vacated by the preceding removed bottom unit.

11. An air filter comprising: a frame; a vertical stack of filter units supported in air filtering position through the engagement of its bottom unit with said frame; a conveyor mechanism for intermittently removing the bottom unit of the stack and replacing it at the top thereof; the weight of the stack being effective, upon the removal of each bottom unit, to cause the succeeding lowermost unit of the stack to move gravitationally downward into the stack-supporting position vacated by the preceding bottom unit; a rotatable member mechanically connected to and driven by the stack during the lowering movement thereof; and clutch means interposed between said conveyor and rotatable member to control the rate of the lowering movement of the stack, said clutch means being operative to connect said member to said conveyor when a bottom unit is removed from the stack-supporting position, and to disconnect said parts when said bottom unit is replaced by the succeeding unit of the stack.

ARTHUR NUTTING.
